LOOM SHUTTLE

John J. Kaufmann, Jr., Greenville, S. C., assignor
to Steel Heddle Manufacturing Company,
Philadelphia, Pa., a corporation of Pennsyl-
vania

Application March 4, 1944, Serial No. 525,005

4 Claims. (Cl. 139—217)

1

My invention relates to shuttles for looms, and it relates more particularly to the provision of improved means, in such shuttles, for maintaining the proper tension on the filling yarn as the shuttle is picked back and forth through successive sheds of the warp.

In the shuttles which are used in the modern types of automatic looms, there is usually provided a threading block at the rear end of the shuttle which is provided with means for automatically causing the filling yarn to be threaded in the shuttle immediately after the bobbin has been replenished in the shuttle. Such threading blocks are made in various shapes and styles, and in some instances, where it is desirable to control, more or less accurately, the tension of the filling thread, said threading blocks are provided usually at the end thereof to which the filling thread is fed from the bobbin to the threading block, with spring pressed members between which the thread travels as it passes to the channel of the threading block, and thereby there is provided a uniform tension on the filling yarn as the shuttle passes from side to side in the operation of the loom.

In the tension devices heretofore provided, particularly where springs were used for pressing the tension members toward each other, it sometimes occurred that, when the reversal of the movement of the shuttle took place, the filling thread would overrun and throw a loop into the space behind one or the other of the tension members and become fouled on the tension spring.

Also there was a tendency of the lint from the filling yarn to pass into said space and pack behind the tension members rendering the same ineffective and causing the tension members to unduly bind the filling thread.

The object therefore of the present invention is to provide an improved form of tension device for automatically threading shuttles which is so constructed and arranged that fouling of the filling thread on the tension springs is eliminated, as is also the tendency of the lint to collect and pack behind the tension members from time to time.

The nature and characteristic features of the invention will be more readily understood from the following description, taken in connection with the accompanying drawing forming part hereof in which:

Fig. 1 is a top or plan view of the threading end portion of a loom shuttle having a tension

2

device mounted therein embodying the main features of the present invention;

Fig. 2 is a longitudinal central sectional view of the shuttle shown in Fig. 1;

Fig. 3 is an enlarged end elevation of the threading block detached from the shuttle, illustrating more particularly the position of the tension members therein;

Fig. 4 is an enlarged longitudinal section of 10 the inner end portion of the threading block detached;

Fig. 5 is an enlarged underneath plan view of 15 the inner end portion of the threading block;

Fig. 6 is a sectional view taken approximately 20 on the line 6—6 of Fig. 4, still further enlarged;

Figs. 7 and 8 are respectively side elevations, 25 on a scale similar to Fig. 6, of the tension members detached; and

Figs. 9 and 10 are underneath plan views 30 thereof.

It should, of course, be understood that the 35 description and drawing herein are illustrative merely, and that various changes and modifications may be made in the structure disclosed 25 without departing from the spirit of the invention.

Referring to the drawing, in the particular 40 embodiment of the invention therein shown, the shuttle body 10 is preferably made of wood and has the usual bobbin chamber 11 in which the bobbin 12 is held by the usual means (not shown) whereby it may be readily discharged therefrom and a new bobbin substituted as the filling runs out from time to time.

The shuttle body 10 is also provided with the 45 usual side delivery eye 13 for the passage of the filling yarn 14. The sides of said eye may be protected by hardened steel pins 15 and 16, or the like, to take the wear caused by the run of the filling.

The threading block 17 comprises primarily a casting, preferably made of metal, either cast iron or brass, as desired. Said block 17 has its outer side surfaces 18 and 19 preferably parallel with each other and its bottom surface 20 substantially at right angles thereto. The body portion of the threading block 17 is fitted into a complementally shaped groove 21 in one end of the body portion 10 of the shuttle.

The body portion of the threading block 17 is 50 provided with a longitudinal channel 22 through which the filling thread 14 passes to the side delivery eye 13 during the weaving operation as said filling is laid into the cloth.

The threading block 17 may also be provided 55 with a rearwardly extending horn portion 24 and

an intermediate horn portion 25 extending into the longitudinal channel 22 of the threading block 17, said portion serving to assist in the initial threading of the block and in the retention of the filling thread therein, after the initial threading operation has been completed.

At the inner end of the threading block 17, that is the end disposed toward the bobbin, there is mounted a pair of tension members 26 and 27. The inner end of the threading block 17 is recessed vertically as at 28 for the mounting of said tension members 26 and 27 therein. The lower ends of the tension members are provided with suitable apertures 29 through which extends a pin 30 mounted in the lower portion of the inner end of the threading block 17.

The upper end of each of the tension plates is bent over as at 31 to provide lug-like extensions 32 which are positioned respectively in suitable apertures 33 drilled in the upper portion of the inner end of the threading block 17. In this manner the tension plates are guided at both the top and the bottom.

For the purpose of imparting the requisite tension to the members 26 and 27 so that the same will grip the filling thread as the same passes therebetween, there are provided coil springs 34, which are positioned in hollow screws 35 which are threaded in the side walls of the threading block in vertical alignment with the guide pin 30, at the bottom and the guiding apertures 33 at the top. The hollow screws 35, in which the springs 34 are mounted serve to provide means for regulating the degree of tension on the members 26 and 27.

The main or body portions of the tension members 26 and 27 may be of any desired configuration in cross section, as for example, they may be provided with flat faces 36 and have angularly disposed flanges 37 along the side margins thereof which are disposed within the thread channel, and the similar angularly disposed flanges 38 along the thread entrance side thereof each have a further extending flange 39 substantially at right angles to the main faces.

The additional flanges 39 are disposed on the side toward the bobbin chamber and extend into additional grooves 40 provided in the inner face of the threading block 17, overlapping the edges of the inner recess, thereby effectively preventing the entrance of loops which may occur upon reversals of motion of the shuttle, or when for any reason the thread overruns, and also effectively serving to prevent dust and lint from the filling thread from passing into the space behind the tension plates, enabling the same to function effectively at all times without interference from such sources.

I claim:

1. In a loom shuttle of the automatically threading type having a threading block mounted in one end thereof and having a longitudi-

nal thread channel through which the filling thread passes from the bobbin to the outlet, tension members mounted in the threading block, springs mounted in the threading block pressing the tension members toward each other, angularly disposed portions along the sides of the tension members, and an additional laterally extending flange along the thread entrance side of each of the tension members, said flanges overlapping the sides of the thread channel at the entrance end thereof thereby to provide guards to prevent thread loops and lint from passing behind the tension members.

2. In a loom shuttle of the automatically threading type having a threading block mounted in one end thereof and having a longitudinal thread channel through which the filling thread passes from the bobbin to the outlet, tension members mounted in the threading block, springs mounted in the threading block pressing the tension members toward each other, the threading block having a recess, at the entrance end of the thread channel, and the tension members having portions extending into the sides of said recess and overlapping the sides of the thread channel thereby to provide guards to prevent thread loops and lint from passing behind the tension members.

3. In a loom shuttle of the automatically threading type having a threading block mounted in one end thereof and having a longitudinal thread channel through which the filling thread passes from the bobbin to the outlet, tension members mounted in the threading block at the entrance end of the thread channel, springs mounted in the threading block and pressing the tension members toward each other, the threading block having a recess at the entrance end of the thread channel, and the tension members having portions extending into the sides of said recess and overlapping the sides of the thread channel thereby to provide guards to prevent thread loops and lint from passing behind the tension members.

4. In a loom shuttle of the automatically threading type having a threading block mounted in one end thereof and having a longitudinal thread channel through which the filling thread passes from the bobbin to the outlet, tension members mounted in the threading block at the entrance end of the thread channel, springs mounted in the threading block and pressing the tension members toward each other, the threading block having a recess at the entrance end of the thread channel, and flanges along the sides of the tension members extending into the side portions of said recess and overlapping the sides of the thread channel thereby to provide guards to prevent thread loops and lint from passing behind the tension members.
